WILLIAM F. CAULEY, OF WADE, MISSISSIPPI.

WASHING IMPLEMENT.

1,271,852.

Specification of Letters Patent.

Patented July 9, 1918.

Application filed March 7, 1916. Serial No. 82,677.

To all whom it may concern:

Be it known that I, WILLIAM F. CAULEY, a citizen of the United States, residing at Wade, in the county of Jackson and State 5 of Mississippi, have invented certain new and useful Improvements in Washing Implements, of which the following is a specification.

This invention relates to improvements in 10 washing implements.

The principal object of the invention is to provide an implement of this character which will include a pair of suction cups so arranged that one may act as a pivot for the 15 other so that they may be rocked.

Another object of the invention is to provide a washing implement of this character which will be easy of operation, the same being so constructed as to relieve strain due 20 to the fact that the cups do not have to be lifted clear of the water in order to break the partial vacuum therein.

A further object of the invention is to provide suction cups having openings therein to permit of ingress of air to break the partial vacuum and to provide means to cause the air to take a tortuous path in its flow to the cups so that the partial vacuum may be prolonged.

30 A further object of the invention is to provide in any implement of this character means to pound the articles to be washed during operation of the implement.

With the above and other objects in view 35 the invention consists in the novel features of construction, combination and arrangement of parts as will be hereinafter more fully described, illustrated in the accompanying drawings and claimed.

40 In the drawings:

Figure 1 is a vertical sectional view of a washing implement constructed in accordance with the invention; and

Fig. 2 is a bottom plan.

45 Referring to the drawings by numerals wherein is illustrated the preferred embodiment of my invention 1 and 2 designate a pair of substantially frusto-conically shaped hollow suction cups which are connected in 50 spaced relation by means of brackets 3, a plurality of these brackets being provided whereby the cups are held in rigid relation and to provide means whereby an operating handle, indicated at 4, may be applied to the 55 implement for operating the same. Each of

the cups 1 and 2 is of a similar construction. It is thought therefore that a detail description of but one, together with its method of operation in connection with the other will suffice for both.

The lower ends of each of the cups are open and the edges thereof are rolled so as to provide smooth surfaces for engagement with the articles to be washed and to prevent cutting or fraying of the same. Intermediate the upper and lower ends of the cups a horizontally extending partition 5 is provided. This partition is provided with a flange 6 for engagement with the inner wall of the cup, whereby the same may 60 be rigidly secured therein. This partition is outwardly bulged toward the upper end of the cup and is provided with a plurality of openings 7 arranged near its edge and in spaced relation. A central opening is provided in this partition which communicates with the upper open end of a substantially horizontal frusto-conically shaped member 8, the said member 8 being extended downwardly relative to the partition and terminating slightly short of the lower open end of the cup 1. The lower end of this member is closed by means of a partition 9 which is inwardly bulged toward the upper open end 65 of the member and which has formed there- 70 in a plurality of spaced openings 10.

Formed on or secured to the outer lower end of the member 8 is the lower end of a cup member 11 which has its side walls extended upwardly and outwardly relative to 75 the member 8 and abuts with the under face of the partition 5 to which it is secured in any suitable manner. This cup member is provided adjacent its lower edge in the side walls thereof with a plurality of spaced 80 openings 12, these openings being disposed below similar openings 13 in the side walls of the member 8.

The upper end of the cup 1 is closed as indicated at 14 and this closed upper end 85 has secured thereto upon its inner face the upper end of a frusto-conically shaped member 15 which has its lower end abutting with the partition 5, to which it is secured in any suitable manner. This second frusto-conical member 15 is centrally arranged within the cup and has its lower end open so as to be 90 in communication with the upper open end of the member 8. Openings 16 are formed 95 in the side walls of the member 15 interme- 100 diately above the openings 12. Openings 17 are formed in the side walls of the member 15 interme- 105 diately above the openings 13. Openings 18 are formed in the side walls of the member 15 interme- 110 diately above the openings 16.

diate its ends and these openings are arranged slightly above similar openings 17 in the side walls of the cup.

From the construction described it will be noted that the handle 4 may be grasped and swung laterally so that one of the cup members bearing upon the articles to be washed will act as a pivot or fulcrum for the other, it being understood that the implement is adapted to be inserted in a tub or the like containing the articles to be washed and the same oscillated to accomplish the desired purpose.

When one of the cups is moved downwardly into engagement with a wet garment to be washed, it is obvious the movement of the cup will be rapid. The lower portions of the suction cup which, as above specified is being moved rapidly downward, will produce a pounding action for assisting in cleansing the articles pounded thereby. It is of course obvious that the wet garment will be very flexible and as a result when the suction cup and partition engage the garment it will 25 change to conform to the shape of the interior of the particular cup engaging the garment. As a result, the garment will quickly pass up in between the exterior of the cup 11 of the particular suction cup 1 and the 30 interior of the suction cup, thus forcing the air from between these elements either through the openings 12 or around under the lower end of the suction cup. The air will also be forced from under the partition 9, 35 constituting a partial vacuum at this point, since the openings 10 are in the plane below the upper portion of the partition 9. However, the greater partial vacuum is formed at this time above the openings 12 and between the cup 11 and the suction cup. This 40 partial vacuum between the latter mentioned elements is caused by the quick movement of the garment up in between these elements, thus causing the air to be partially and very quickly expelled. As the cup thus referred to moves downwardly, it is obvious the expelling of the air through the various openings will permit the water in the vessel in which the washing implement is positioned 45 to pass through these openings and also up under the suction cup to partially fill with water the frusto-conically shaped members from which the air has thus been partially expelled. Owing to the arrangement of the 50 openings in the suction cup and the members and elements connected thereto, it is obvious that when the suction cup is moved upwardly, it will require some little time before the water is expelled and the air which is 55 passing into the upper portion of the suction cup through the openings 17 finds its way downwardly through the conically shaped members to the space below the partition 9 as well as the space between the cup 60 11 and the interior of the suction cup there-

adjacent. As will be noted, the partial vacuum, caused by the rarefied air within the space between the cup 11 and the suction cup, will be sufficient to quickly draw the garment therebetween, upwardly for a slight 70 distance, before the passing of the air through the upper portion of the suction cup to its lower portion will break the vacuum and permit the garment to fall from engagement with said cup back into the vessel in 75 which the washing implement is being oscillated.

In this connection, special attention is directed to the fact that the device is actuated very rapidly and for this reason the garment 80 will be forced upwardly in between the suction cup and the cup member 11 very quickly, to expel the air and water therefrom, to form the partial vacuum, by causing a rarefaction of the air therein. As a result, a 85 quick upward movement on the part of the cup will draw the garment upwardly for a slight distance before the reentering of the air breaks the partial vacuum. Thus it will be noted that the entire stress is not brought 90 to bear upon the partition 9, but also between the cup 1 and the cup member 11 above the openings 12.

From the foregoing description taken in connection with the accompanying drawings 95 it is thought that the construction and operation of the improved washing implement will be clearly understood, and while I have herein shown and described one specific embodiment of my invention I do not wish to 100 be limited thereto except for such limitations as the claims may impart.

I claim:

1. In a washing implement, a pair of main cup members, connections between said members, a handle mounted in said connections, a curved partition positioned transversely in each cup member, a frusto-conical member depending from each partition and having an open upper end forming a central 110 opening for said partition, a frusto-conical member positioned between each partition and the bore of the main cup member, said frusto-conical members having openings in 115 their sides, said main cup members having openings in their sides above said partitions, and auxiliary cup members positioned in the lower portions of said cup members and provided with openings in their lower portions and their side portions, the lower portions of said auxiliary cup members serving to close the lower ends of the first-mentioned frusto-conical members.

2. In a washing implement, a main inverted cup member, a curved horizontal partition positioned in said main inverted cup member and provided with openings, a frusto-conical member depending from the circular opening of said partition, an auxiliary cup member connected with said parti- 125 130

tion and having a curved bottom portion forming the bottom of the frusto-conical member, said auxiliary cup member and frusto-conical member having offset openings in their side portions, the bottom portion of said auxiliary cup member being provided with openings, said main inverted cup member having openings in its side portions above said partition, and a second 10 frusto-conical member resting upon said

partition and having openings offset from the openings of said main inverted cup member.

In testimony whereof I affix my signature in presence of two witnesses.

WILLIAM F. CAULEY.
